AUTOMATIC-SPRINKLER CLOSER.

1,028,247.

Specification of Letters Patent.

Patented June 4, 1912.

Application filed June 1, 1904. Serial No. 210,638.

To all whom it may concern:

Be it known that I, LEONARD D. MOREY, of Watertown, in the county of Litchfield and State of Connecticut, have invented 5 certain new and useful Improvements in Automatic-Sprinkler Closers; and I do hereby declare the following specification, taken in connection with the accompanying drawings, forming a part of the same, to be a 10 full, clear, and exact description thereof.

In the case of a fire in a building equipped with automatic sprinklers it frequently happens that for one cause or another the water cannot be shut off promptly after the 15 sprinklers have operated and after the fire in the vicinity of the opened sprinklers has been extinguished, with the result that a greater or less amount of water damage is occasioned by the flow of water from the 20 open sprinklers, which could be prevented if means were at hand for promptly closing the individual sprinkler or sprinklers that had become opened and so as to shut off the flow of water therefrom. So also it sometimes happens that a sprinkler becomes 25 opened accidentally and when there is no fire to be extinguished, and it would be of great advantage to be able to promptly close such opened sprinkler without shutting off 30 the water from the entire sprinkler system, or that portion thereof upon which such opened sprinkler is located.

The object of the invention is to provide a 35 convenient and efficient means for thus closing an opened sprinkler and preventing the flow of water therefrom, when it is either inconvenient or undesirable to shut off the water from the sprinkler system.

To that end the invention consists in the 40 novel construction and combination of parts hereinafter described and claimed.

Referring to the drawings, Figure 1 is a 45 plan view of the sprinkler closer; Fig. 2 is a side view; Fig. 3 is a side view showing the device in place in a sprinkler and closing the outlet thereof; Fig. 4 is a view at right angles to Fig. 3, and showing the device in cross section; Fig. 5 is an end view

of Fig. 2; Figs. 6, 7, and 8 show means for inserting the closer in place and the manner 50 of using the same.

The device consists of two legs or members a a' pivoted together at b . To one of the members, as a , is attached a valve c , preferably by being pivoted thereto as 55 shown. The other member a' is preferably provided with projecting ears a^2 a^2 adapted to engage the frame of the sprinkler A and form stops to locate the valve c in line with the outlet of the sprinkler. 60

Secured to one leg of the device, as a' , is a link d preferably formed of elastic sheet metal and so as to constitute a spring, and provided with slots or openings d' . To the other leg is secured a lug or projection e 65 the end of which is preferably beveled as shown. Preferably a spring f is located between the legs a a' , said spring serving to keep the legs or members in the position shown in Fig. 2. 70

The mode of using the device is as follows: The device with the parts in the position shown in Fig. 2 is inserted within the frame of the sprinkler until the ears a^2 a^2 bring up against said frame, which will 75 locate the valve c in line with the outlet of the sprinkler. By pressing or pulling the separated ends of the legs a a' together the opposite ends of said legs will be separated and so as to force the valve c against the 80 valve seat of the sprinkler, the sprinkler frame serving as an abutment. This operation causes the spring link d to pass along the beveled end of the lug e until when the valve is firmly seated said lug e will be 85 caused to enter one of the slots d' , thereby holding the legs a a' in the position shown in Fig. 3 and so as to hold the valve c to the valve seat of the sprinkler. If desired the lug e instead of being rigidly secured to the 90 leg a may be secured thereto by an easily fusible solder, and so that in case the device should be accidentally left in place until a fire should again break out, the melting of the solder would release the lug e and consequently release the valve and thereby per-

mitting the device to fall out of place and thus insure the automatic opening of the sprinkler.

As the closing device above described will require to be inserted in place while the sprinkler is operating and discharging a shower of water, and also because there may not be at hand a step ladder or other means for enabling a person to conveniently reach the sprinkler, which is located near the ceiling, it will be desirable to provide some means for inserting the device from a position upon the floor. Such means are shown in Figs. 6, 7, and 8, said means consisting of a staff g provided with a socket g' at its upper end adapted to receive a tang g^2 secured to one of the legs $a a'$. As the sprinklers, instead of being located upright above the pipe, are sometimes arranged to extend downward from the pipe, thereby reversing the position of the valve seat, it will be convenient to provide each of the legs $a a'$ with a tang g^2 , so that the closing device may be inserted in the staff g with the valve c in reversed position. A wire h arranged to slide in an eye h' secured to the staff has its upper end bent over to form a hook h^2 and so as to overlie the upper leg of the closing device as shown in Fig. 8. Preferably the socket g' and the tangs g^2 are made rectangular in shape to insure the insertion of the tang in the socket so as to bring the leg of the device in proper position to be engaged by the hook h^2 . The lower end of the wire h is connected to a lever i pivoted to the staff, which lever may be provided with a suitable handle. When the closing device is to be inserted in a sprinkler the proper tang g^2 is inserted in the socket g' , with the hook h^2 overlying one of the legs $a a'$, and by means of the staff the operator is enabled to insert the device from the floor, as illustrated in Fig. 8. When the device has been properly located in the sprinkler to bring the valves c in line with the outlet, the lever i is depressed, which causes a downward pull on the wire h and hook h^2 , thereby operating the underlying leg of the closing device to close the valve c against the valve seat in the sprinkler. When the valve has been brought to its seat it will be held thereby by the engagement of the spring link d with the lug e . The hook h^2 may then be raised and the staff withdrawn.

It is evident that the mechanical construction of the device and of the operating means may be widely varied without departing from the principle of the invention.

The several slots in the spring link f serve to adapt the device for use in connection with different forms or constructions of sprinklers, or sprinklers in which the distance from the valve seat to the opposing portion of the frame varies.

What I claim as my invention and desire to secure by Letters Patent is:

1. An automatic sprinkler closer comprising two members, one adapted to engage the frame of a sprinkler and the other provided with a valve for closing the sprinkler nozzle, one of said members being movable with relation to the other to force said valve against the valve-seat of the sprinkler, means for holding the valve in position to close the sprinkler nozzle, and means for automatically releasing said valve in case of fire, substantially as described. 70

2. An automatic sprinkler closer comprising two members pivoted together, a valve connected to one of said members, and fusible means for connecting said members to hold said valve to the valve seat of a sprinkler, substantially as described. 80

3. An automatic sprinkler closer adapted to be inserted between the valve seat and the opposing frame of an automatic sprinkler and comprising two members pivoted together, a valve connected to one of said members, and means for connecting said members to hold said valve to the valve seat of the sprinkler by the engagement of the other member with the frame of the sprinkler, substantially as described. 85

4. An automatic sprinkler closer comprising two members pivoted together, a valve connected to one of said members, and a spring catch for connecting said members beyond the pivot, substantially as described. 90

5. An automatic sprinkler closer comprising two members pivoted together, a valve connected to one of said members, a catch on one of said members and a spring link connected to the other member and adapted to engage said catch, substantially as described. 100

6. An automatic sprinkler closer comprising two members pivoted together, a valve connected to one of said members, a catch on one of said members, and a spring link connected to the other member and provided with a series of openings adapted to engage said catch, substantially as described. 110

7. The combination of an automatic sprinkler closer and a detachable staff adapted to receive said closer and by means of which closer may be located in position in a sprinkler, substantially as described. 115

8. The combination of an automatic sprinkler closer, a detachable staff adapted to receive said closer and by means of which the closer may be located in position in a sprinkler, and means for operating the closer to close the outlet of said sprinkler, substantially as described. 120

9. The combination of an automatic sprinkler closer, a staff adapted to receive said closer and by means of which the closer may be located in position in a sprinkler, and a sliding member carried by said staff 130

for operating the closer to close the outlet of said sprinkler, substantially as described.

operating the closer, and a lever for operating said sliding member.

10. The combination of an automatic sprinkler closer, a staff adapted to receive
5 said closer and by means of which the closer may be located in position in a sprinkler, a
sliding member carried by said staff for
